UNITED STATES PATENT OFFICE.

ALBERT NEAL, OF KOKOMO, INDIANA.

LIFTING-JACK.

1,151,962.

Specification of Letters Patent. Patented Aug. 31, 1915.

Application filed April 19, 1915. Serial No. 22,430.

To all whom it may concern:

Be it known that I, ALBERT NEAL, a citizen of the United States, residing at Kokomo, in the county of Howard and State of Indiana, have invented certain new and useful Improvements in Lifting-Jacks, of which the following is a specification.

The object of this invention is to provide a lifting jack for pulling stumps, stretching wire, lifting heavy objects such as automobiles, wagons, stone, railroad rails and the like, wherein by a single lever the staff or head of the jack will be advanced or retracted by the manipulation of said lever, or entirely released by other of its movements.

I accomplish the above and other objects which will hereinafter appear by the mechanism illustrated in the accompanying drawings, in which—

Figure 1 is an end elevation of my improved jack; Fig. 2 a section on the line 2—2 of Figs. 1 and 3; Fig. 3, a section on the line 3—3 of Fig. 2; Fig. 4, a section through the line 4—4 of Fig. 3, and Fig. 5 a side elevation of the inner end of the lever showing the two pawls which the lever carries.

Like characters of reference indicate like parts throughout the several views of the drawings.

The standard 6 has an expanded base 7 and has a longitudinal opening 8 in which a staff 9, makes a close sliding fit. The staff has a longitudinal rib 10 which enters and fills a slot in the standard and on the same side of the latter is an extension 11, to engage objects in some instances which are to be moved by the jack. The lower end of the staff has an eye 12 for the attachment of a wire or the like to be stretched, and at its opposite and upper end is a head 13 to contact the load. The staff also has notches 14 opposite the rib 10 which are engaged by pawls 15 and 16, carried by a lifting lever 17. The standard has a hollow extension 18, which is open at the bottom and lower front for the introduction and operation of the lever 17, and the sides of which extension have inner recesses 19 in the bottoms of which trunnions 20 on the lever 17 are journaled. Said recesses communicate with others, 20', extending to the lower edges of the extension-walls whereby the trunnions are readily inserted and removed. The pawls 15 and 16 operate through a suitable opening 21 in the partition separating the hol-

low interior of the extension from that of the standard, with the notched bar.

The inner end of the lever has a top channel 22, notched from the top on opposite side-walls to receive shafts 23 and 24, respectively, on which pawls 15 and 16 are mounted. The shafts are flattened on one side to pass through restricted mouths of the slots at certain positions of the pawls for assembly. Springs 25 and 26 are wrapped around the respective shafts and have their outer lower ends in contact with the bottom and adjacent side of the channel in the lever, and the inner and upper ends in contact with notches in their pawls formed by recessing the pawls as shown. The springs act doubly, that is, to move the outer ends of the pawls toward the notched staff and to press the pawls in a direction opposite to their sides on which the springs are placed. The pawl 15 has a lug 27 on the side opposite said spring, near its free end, which contacts by the action of the spring on the pawl with a lug 28 on the inner wall of extension 18, at certain positions of the lever, and at other positions of the lever with a cam rib 29, above the lug 28. The pawl 16 has a similarly located lug 30 which contacts with a lug 31 on the inner wall of the extension 18. The lugs are all beveled to allow the pawls 15 and 16 to swing out freely, but to hold them out during the opposite—upward—stroke of the lever until they have passed around their respective stationary lugs on their opposite sides from the staff, and over them, and are brought into play during the step-by-step retraction of the staff.

The two adjacent faces of the pawls have the respective lugs 32 and 33 which contact with each other when the lever is lowered its maximum distance causing pawl 15 to be swung out farther than would otherwise obtain and as a result, causing its lug to pass over the cam-rib 29, further delaying the return contact of the pawl with the notched staff when the lever is raised, and it is not permitted by the cam-rib to contact the staff until after the pawl 16 has been withdrawn from the staff by the upward movement of the lever. By this means the support of both pawls is removed and the maximum retraction of the staff will occur at once by gravity.

Fig. 2 shows the lever and pawls in position for advancing the staff a notch at a

time. By a medium oscillation of the lever the pawls will be brought alternately into engagement with the notched staff and the latter moved outwardly of the standard. 5 But by a further downward movement of the lever the pawl 15 will be moved far enough to cause its lug 27 to pass the lug 28, against which it will be thrown by the oblique lower face of the cam-rib on the upper stroke of the lever and the pawl will be held out of engagement so as to miss the next notch but will enter the one above that by an upward swing of the lever further than is right for lifting. Such further lever 10 movement upwardly passes the lug 30 of the pawl 16 outside of the fixed lug 31, and that pawl is held by said lugs from entering the next notch in the staff, and so on.

Having thus fully described my invention, 20 what I claim as new and wish to secure by Letters Patent of the United States, is—

1. In a lifting-jack, a standard, a notched staff mounted in the standard, a lever pivoted to the standard, a pair of pawls pivoted 25 to the lever on opposite sides of the lever pivot and alternately engaging the notched staff by the rocking of the lever, means by a greater angular movement of the lever to

alternately hold the pawls out of engagement with the next notch above to retract 30 the staff comprising lugs on the side of the pawls and adjacent lugs on the inside of the standard, and springs pressing the pawls into engagement of the lugs with those of the standard. 35

2. In a lifting-jack, a standard, a notched staff mounted in the standard, a lever pivoted to the standard and pawls pivoted to the lever on opposite sides of the lever pivot 40 alternately engaging the notched staff by the rocking of the lever, means by a greater angular movement of the lever for releasing both pawls comprising lugs on the sides of the pawls and lugs and a cam-rib on an inner adjacent wall of the standard 45 and other lugs on adjacent sides of the pawls adapted to contact each other when the lever is lowered its maximum distance.

In witness whereof, I have hereunto set my hand and seal at Indianapolis, Indiana, 50 this 18th day of February, A. D. one thousand nine hundred and fifteen.

ALBERT NEAL. [l. s.]
